UNITED STATES PATENT OFFICE.

CHARLES CAMPBELL AND JOHN ANGUS CAMERON, OF METROPOLIS, ILLINOIS.

CHIMNEY-SWEEPER.

1,297,090.

Specification of Letters Patent. Patented Mar. 11, 1919.

Application filed July 9, 1917. Serial No. 179,468.

To all whom it may concern:

Be it known that we, CHARLES CAMPBELL and JOHN ANGUS CAMERON, citizens of the United States, residing at Metropolis, in the 5 county of Massac and State of Illinois, have invented new and useful Improvements in Chimney-Sweepers, of which the following is a specification.

This invention relates to an apparatus for 10 sweeping chimneys, primarily designed to be installed in the flues at all times, and one which may be easily and conveniently manipulated to facilitate the cleansing of the soot collected in the flue, in an efficient and 15 expeditious manner.

An object of the invention resides in the production of an apparatus of the above 20 stated character which may be manufactured and sold at a comparatively low cost, and one primarily designed to permit of the soot, 25 upon being dislodged from the walls of the flue, to be discharged at a point below the point of installation of the apparatus within the flue, consequently, preventing the soot from effecting the operation of such apparatus.

With the above and other objects in view, 30 the invention consists in the novel features, details of construction and combination of parts which will hereinafter be more fully 35 set forth, illustrated in the accompanying drawings and pointed out in the appended claim.

In the drawings:

35 Figure 1 is a front elevation of the apparatus installed in a flue, the flue being partially shown in section;

Fig. 2 is a side elevation with the flue shown in vertical section;

40 Fig. 3 is a top plan view;

Fig. 4 is a section taken on line 4—4 of Fig. 1;

Fig. 5 is a section taken on line 5—5 of Fig. 1; and

45 Fig. 6 is a view similar to Fig. 1, showing a slightly modified form of soot collecting device.

Referring more particularly to the accompanying drawings, in which like characters of reference refer to corresponding 50 parts in the several views, and in order that a clear understanding of the invention may be had, the sweeping apparatus denoted generally by the character 5 is illustrated as 55 installed within a chimney flue A at a point

below the stove pipe receiving opening B thereof.

For convenience in installing this apparatus within the chimney flue, an opening 6 is formed in the front wall A of said flue at 60 a point below the pipe receiving opening B, and for obstructing the view of this opening, when the device is not in use, we employ a closure plate 7 having a flange 8 adapted to tightly contact with the wall of 65 the opening 6 to prevent any accidental dislodgment of the plate from said opening.

The sweeping apparatus embodies a table 9 of skeleton form, lying transversely of the flue with the innermost extremities 10 inserted in cut-outs 11 formed in the rear wall 12 of the flue, while the forward extremities 13 of the table extend within the opening 6 and repose upon the bottom wall thereof. During the operation of cleansing the flue 75 and for preventing the soot dislodged from the walls thereof from being discharged through the openings 6, use is made of an inner closure plate 14 centrally formed with an opening 15. Provided on the table 9 is a 80 pair of spaced bearings 16 in which is journaled a drum 17 carrying a cable 18. This cable 18 is trained over a loosely mounted pulley 19 journaled in the spaced bearings 20 formed contiguous with a hanger 21. To 85 facilitate the mounting of this hanger across the open upper end 22 of the flue, we provide on the opposite terminals of the hanger spurs 23 which penetrate, to an extent, the flue and prevent any accidental creeping 90 movement of the same to non-align the pulley 19 centrally of the drum 17.

The character 24 denotes a brush head embodying a substantially rectangular frame 95 having secured to its respective top and bottom faces, through the employment of a bolt and nut connection 26, spaced inwardly converging braces 27 centrally provided with eyes 28 and 29 respectively. These eyes are alined vertically with one 100 another, and the upper extremity 30 of the cable 18 has connection with the eye 29, while the opposite or lower extremity 31 has connection with the eye 28, consequently, as the handle 32 is rotated in one direction, 105 will tend to move the brush head in an upward direction, and upon the rotation of the handle in the opposite direction, will impart a downward movement to the brush head. This operation is repeated until the 110

removal of the soot from the inner wall of the flue has been successfully accomplished. In order to support the table within the flue and prevent the accidental removal of the same therefrom, we provide clamps 33 in the form of turn buckles, with the arms 34 thereof contacting with the upper wall of the opening 6, while the opposite arms 35 of the clamps are engaged in openings 36 of the outer extremities 13 of said table.

For convenience in collecting the soot removed from the walls of the flue during the reciprocation of the brush head 24, we secure to the under face of the skeleton 15 formed table 9 a pan 37 terminating in a discharge spout 38 which protrudes through one of the walls of said flue, consequently, the soot in this particular instance is not only collected but efficiently discharged into 20 a suitable receptacle 39, and thereby preventing any annoyance to the operator in the handling of the soot upon the completion of the cleansing operation of the flue.

In Fig. 6 of the drawing is shown a slight 25 modified form of pan, is noted by the characters 40, wherein the open discharge end of the spouts 41 thereof, projects laterally from the openings 42 provided in the flue. In order that such openings 42 would not 30 mar the appearance, of the flue, we contemplate in providing the cover plate 10^a of sufficient size which when installed will cover the opening 42. This form of pan is provided with a flange 43 through which 35 suitable fastening means 44 projects for securing the pan to the under surface of the skeleton table 9. Obviously as the soot is collected within the pan 40 and after the

pan has been filled, the operator removes the cover plate 10^a and allows the soot contained in the pan 40 to be discharged through its outlet or discharge end.

From the foregoing description, taken in connection with the accompanying drawings, the advantages of construction and the 45 method of operation will be readily apparent to those skilled in the art to which the invention relates, and while we have described the principles of operation of the invention, together with the device which we now consider to be the best embodiment thereof, we desire to have it understood that the device shown is merely illustrative, and that such changes may be made when desired as are within the scope of the 50 55 appended claim.

What is claimed as new, is:—

A device of the class described embodying inner and outer closure plates each provided with an opening and adapted to be mounted 60 in an opening of a flue, a drum adapted to be mounted in the flue in alignment with the openings, a support therefor extending into said first named opening, a brush head, flexible operating members carried by the drum 65 and connected terminally with said brush head, a pulley over which one of said members passes, means located between said closure plates for clamping said support in place, and operating means for said drum 70 journaled in the openings of the closure plates.

In testimony whereof we affix our signatures.

CHARLES CAMPBELL.
JOHN ANGUS CAMERON.
